US00D924567S

(12) **United States Design Patent** (10) **Patent No.:** **US D924,567 S**
(45) **Date of Patent:** **** Jul. 13, 2021**

(54) **CASE FOR EARPHONES**

(71) Applicant: **SPIGEN KOREA CO., LTD.**, Seoul (KR)

(72) Inventor: **Soo Ha Jung**, Seoul (KR)

(73) Assignee: **SPIGEN KOREA CO., LTD.**, Seoul (KR)

(**) Term: **15 Years**

(21) Appl. No.: **29/733,955**

(22) Filed: **May 7, 2020**

(51) LOC (13) Cl. **03-01**

(52) U.S. Cl.

USPC **D3/302**

(57) **CLAIM**

The ornamental design of a case for earphone, as shown and described.

DESCRIPTION

FIG. 1 is a front perspective view of a case for earphone showing my new design according to a first embodiment of my design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view of a case for earphone showing my new design according to a second embodiment of my design;

FIG. 10 is a rear perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view.

The broken lines throughout the drawing figures depict portions of the case for earphones that form no part of the claimed design.
